(57) **CLAIM**

The ornamental design for a wall/ceiling panel, as shown and described.

DESCRIPTION

FIG. 1 is a top plan view of a wall/ceiling panel showing our new design, the bottom plan view being a mirror image; FIG. 2 is a front elevation view thereof; FIG. 3 is a rear elevation view thereof; FIG. 4 is a left view thereof; FIG. 5 is a right view thereof; FIG. 6 is a reduced perspective view thereof; FIG. 7 is a top plan view of the wall/ceiling panel of FIG. 1, rotated approximately 135 degrees clockwise from the position in FIG. 1, in an assembled array of like panels, the bottom plan view being a mirror image; FIG. 8 is a front view of FIG. 7; and, FIG. 9 is a reduced perspective view of FIG. 7. The broken lines shown in FIGS. 7-9 are directed to environment and form no part of the claimed design.

1 Claim, 9 Drawing Sheets
